US00D954092S

(12) **United States Design Patent** (10) Patent No.: **US D954,092 S**
(45) Date of Patent: ** Jun. 7, 2022

(54) **PORTION OF A DISPLAY SCREEN WITH A GRAPHICAL USER INTERFACE FOR A PORTAL SIDE MENU**

(71) Applicants: **Hoffmann-La Roche Inc.**, Little Falls, NJ (US); **Roche Molecular Systems, Inc.**, Pleasanton, CA (US)

(72) Inventors: **Jorge Cancela Gonzalez**, Basel (CH); **Geraint Iwan Davies**, Basel (CH); **Jean-Philippe Guy Roger Guyon**, Pleasanton, CA (US); **Christin Rene Kreml**, Menlo Park, CA (US); **Tommy Park**, Menlo Park, CA (US)

(73) Assignees: **Hoffmann-La Roche Inc.**, Little Falls, NJ (US); **Roche Molecular Systems, Inc.**, Pleasanton, CA (US)

(**) Term: **15 Years**

(21) Appl. No.: **29/744,763**

(22) Filed: **Jul. 31, 2020**

(51) LOC (13) Cl. **14-04**

(52) U.S. Cl.

CLAIM

The ornamental design for a portion of a display screen with a graphical user interface for a portal side menu, as shown and described.

DESCRIPTION

The single FIGURE is a front view of a portion of a display screen with a graphical user interface for portal side menu. The broken lines illustrate a portion of a display screen and form no part of the claimed design.

1 Claim, 1 Drawing Sheet
